Goldsmiths, ATTORNEY

UNITED STATES PATENT OFFICE

FRANCIS DALE WYATT, OF CINCINNATI, OHIO

SWITCHBOARD SIGNAL-LIGHT SOCKET AND RESISTANCE

Application filed December 4, 1923. Serial No. 678,511.

My invention relates to switchboard, and more especially to signal or pilot, lights and means and method of attaching same to the board. I also provide means whereby I can utilize smaller voltage lamps, in high voltage circuit, than have heretofore been used.

By my invention I am able to greatly increase the number of lines and signal lights on a switchboard of a given size, over the 10 number of lights on the switchboards of corresponding size heretofore in use.

My invention enables me to dispense with the color lens heretofore used on a switchboard as I can color the lamp globe which is 15 visible in front of the board.

My invention also provides means whereby I can use lamps of lower voltage than heretofore in the same voltage circuit as heretofore, and obtain increased and more uniform 20 illumination.

In the drawings in which like letters refer to like parts,

Fig. 1 is a side view of a switchboard section showing my invention.

25 Fig. 2 is a front view with the lamp removed.

Fig. 3 is a sectional view through the switchboard, showing my signal lamp and a diagrammatic view of the connecting electrical circuits.

In the drawing A is the panel board, of suitable insulating material, through which is an opening corresponding in size with the outer wall of the metal signal lamp holder or socket 35 and contact B. This lamp holder or socket and contact B, preferably cylindrical in form has in its wall oppositely arranged channels L to receive the pins on the opposite sides of the lamp. These channels L are so arranged at their inner ends that the lamp may be turned and the pins will engage with the channel to lock the lamp in place. The lamp is held there by the pressure of the spring R which through contact Q holds the 40 lamp in position in the off set ends of the channels L. Surrounding the holder B and held on the end of same is a button or guard cap D preferably of insulating material which is held between the panel A and the end 50 of the holder or socket B by the flange C which

engages with a corresponding flange N on the button or guard cap D. By counter-sinking the flange N of the cap D so that the flange C of the holder B is located below the surface of the button or cap D, I provide a protection or guard around the lamp, give a more finished effect to the board, and insulate the end of the holder B. On the opposite end of the holder B, I provide suitable threads on to which is placed a metal nut ring E which holds the holder B in fixed position in the panel A. Next to the metal nut ring E is a metal washer ring G which is held in contact with nut E by a metal lock ring F. Integral with and projecting out from the washer ring G is a terminal O on to which the wire H is fixed by screw I, nut J and lock nut K.

In the holder B from a point adjacent to position of the end of the lamp I provide an insulating member M having an opening 70 through its longitudinal center in which is located the terminal stud S. On the front end of the stud S, I provide a tube P preferably of brass which is sweated on to the end of the stud S. The edge of this tube is rolled inward so as to form a retaining means for the contact spring R. If desired the stud S and the tube P could be made in one piece. Within the front end of the tube P is arranged the electrical contact Q which is normally held forward, so as to make constant contact with the lamp contact end, by the spiral spring R. The insulating member M, the stud S and the tube P are all held in fixed position with respect to each other by the nut T. Integral with the post S is a post V of smaller diameter upon which is fixed a resistance coil W to the end of which is attached and held fixed the wire X of the circuit by washer Y and terminal screw Z. The resistance coil W is of a material having a high temperature coefficient, or ballast resistance, so that the resistance increases as the current and consequently the temperature increases. When so used in series with a tungsten filament lamp, the resistance will have a steady-ing effect on the lamp and maintain the current in the lamp and consequent amount of illumination at a nearly uniform value when fluctuations in voltage occur in the supply 95 100

circuit. As will be seen from the foregoing the holder or socket B forms one contact and the contact Q in the tube on the end of the stud S forms the other contact for the lamp. The circuit being from the source of supply through wire X terminal Z resistance W, stud S contact and spring Q, R, lamp and return through socket B washer ring G, terminal O to other wire.

10 Claims—

1. In a device of the character described, a mounting cylinder having its front end portion formed as a receiving socket, a stud within the remaining portion of said cylinder, said 15 stud being solid throughout the major portion of its length but having a recess at its forward end, an insulating member extending about said stud within said cylinder, a resilient contact member within said recess and normally 20 protruding beyond the front end of said stud and a resistance mounted on the rear end of said stud, said cylinder extending over said stud to form a rigid mounting for said stud and insulating member.
2. In a device of the class described, a mounting socket having in the forward end portion thereof means to receive and retain the terminal plug portion of an electric lamp, said socket extending rearwardly from said 25 end portion, a stud enclosed by said rearwardly extending portion of said socket, an insulating member approximating the length of said stud, surrounding the same and centering and retaining said stud in said socket, the rear end of the stud being extended beyond said insulating member and beyond the rear end of the mounting socket, a resistance 30 removably mounted on said extended rear end of said stud in close relation to said socket, a nut forming a spacer between the socket and resistance and a resilient contact mounted on the forward end of said stud in position to engage the lamp contact when said lamp is in mounted position.
3. In a panel board mounting, a sleeve 35 adapted to extend transversely entirely through the panel board and having one end portion formed as a receiving socket for an electric lamp, the socket end of said sleeve being provided with a flange adapted to engage one side of said panel board, the other end of said sleeve carrying means adapted 40 to engage the opposite side of said panel board for locking said sleeve in position in said panel board, a stud extending through said sleeve, an insulating member surrounding said stud and centering and supporting the same in said sleeve, and a resistance 45 mounted on the rear end of said stud and a contact on the forward end thereof in a position to engage a lamp contact when such lamp is in mounted position, said stud acting as one conductor and said sleeve acting as the other conductor of the electric circuit.
4. In a panel board mounting, a sleeve

adapted to extend transversely entirely through the panel board, said sleeve having one end thereof formed as a receiving socket for an electric lamp, the lamp receiving end being provided with a flange adapted to engage one side of the panel board, the other end of the sleeve carrying means adjustable thereon to engage the opposite side of the panel board for fixing the sleeve in position in said board, a stud within the sleeve, insulation 75 spacing, the stud from the sleeve, said stud having a threaded portion extending rearwardly a short distance beyond the rear end of the sleeve, a nut on said threaded portion resting against said sleeve, and a resistance coil threaded to said threaded portion of the stud and resting against said nut, said resistance coil, stud, lamp and sleeve being in circuit.

5. In combination with a panel board, a 85 mounting comprising a sleeve of conductive material adapted to extend transversely entirely through the panel board, said sleeve being flanged at one end and externally threaded at the other end, the flanged end of the sleeve being constructed to hold an electric lamp, insulating material snugly secured in the threaded end of said sleeve, a conductive stud extending centrally through the insulating material and projecting a short distance 90 beyond the rear end of the sleeve, the end of the stud toward the lamp being socketed, a contact member slidably and yieldably mounted in said socket, the rearward end of the stud being threaded throughout its projecting portion, a lamp guard held by the flange of the sleeve against one side of the panel board, a pair of nuts on the threaded end of the sleeve one of which rests against the opposite side of the panel board, a conductive washer held between the nuts and constituting a terminal of the lamp circuit, a resistance coil removably threaded to the projecting end of the stud and a second terminal 95 of the lamp circuit on the rear end of the coil, a nut on the stud for holding the sleeve, stud and insulation in relative fixed position, said nut constituting also a spacer between the resistance coil and the sleeve.

In testimony whereof, I have signed my 115 name to this specification.

FRANCIS DALE WYATT.
